UNITED STATES PATENT OFFICE.

HARRY TORCHIANI, OF CHICAGO, ILLINOIS.

APPARATUS FOR TREATING BARRELS.

1,102,306.

Specification of Letters Patent.

Patented July 7, 1914.

Application filed July 3, 1912. Serial No. 707,649.

To all whom it may concern:

Be it known that I, HARRY TORCHIANI, a citizen of the United States of America, residing at Chicago, in the county of Cook and State of Illinois, have invented a new and useful Improvement in Apparatus for Treating Barrels, of which the following is a specification.

This invention relates to an apparatus for treating barrels, and particularly to means for coating them with pitch. The old pitch in barrels usually is removed by burning out the barrels. This method has the disadvantage that a large volume of smoke is generated, which is obnoxious, and it is also dangerous on account of the inflammability of the pitch. Pitch for pitching barrels is mostly liquefied in kettles built into or associated with open flame furnaces. This method also involves a considerable risk on account of the inflammability of the material used.

An object of the present invention is to depitch barrels by forcing air of a suitable temperature into them, so as to melt the old pitch or burn it out, without an open flame and then to apply a new coat of pitch.

Another object is to convey heated air through a kettle filled with pitch to liquefy the material without the use of a furnace.

Another object of the invention is to provide a method and means for heating air to a very high temperature, for reducing the temperature by increasing the volume of the air and for imparting a whirling movement to the air, to convey the same into the barrel or kettle.

Other objects will be more fully understood by reference to the following specification and the claims appended thereto, and by reference to the accompanying drawing. The latter shows by way of example, an apparatus for performing the method which forms a subject matter of this invention.

In the drawing: Figure 1 is an elevation, partly in section of the apparatus. Fig. 2 is a top plan view of the same.

The air is heated by means of a burner 1, to which the fuel in gaseous or liquid form may be supplied through pipe 2. The construction of the burner itself does not form the subject matter of the invention; it is advisable, however, to use a burner generating a very hot, possibly sootless flame. The burner is disposed within a box or casing 4, provided with an opening 5, to

which the air to be heated may be supplied by means of a blower 5' or such like. This box is in communication by means of pipe 6, with a mixing chamber 7, preferably of cylindrical shape.

The mixing or collecting chamber 7 has a wall, 8, of heat-resisting and heat-insulating material. Another pipe, 9, extending from a pump or blower, 10, serves for conveying forced unheated air into the chamber 7. The air flows through pipe 9 at a speed exceeding the velocity at which the air from casing 4 enters the chamber, and it therefore imparts to the heated air a rapid movement. Pipe 9 preferably is disposed in angular direction with respect to a radius drawn to the point where the pipe opens into the wall of chamber 7, imparting thereby a tangential whirling movement to the heated air. The chamber 7 has two outlets, from which the conduits 11 and 12 lead to the depitching device 13, and pitching device 14, respectively. The conduits or pipes 11 and 12 may be provided with suitable valves or dampers 20, to regulate the flow of the heated air from the collecting chamber. The pipe 11 extends through the barrel seats 15, with which the injector nozzles 16 are associated; the latter branch off preferably in vertical direction from the pipe 11 and project through apertures 17 in the barrel seats. Flues 18 lead to the smoke stack 19, from the interior of the barrel seats, and serve for carrying off the obnoxious smoke and odors incidental to all operations where heated pitch is handled.

The pipe 12 is connected by means of coupling 21 with a pipe 22, shown in form of a coil and disposed within the pitch kettle 23. After being conveyed through the material in the kettle the heated air is discharged through riser 24 into the atmosphere, or it may be conveyed to some other place to be utilized. The pitching device shown includes a barrel seat 25 in communication with a pump or tank 26 in the interior of the kettle.

28 indicates the lever of the pump or some other means having a check valve for forcing liquefied pitch from the kettle into the tank and from there into the nozzle 27 of the barrel seat. It is obvious, however, that other pitching devices may be used and reference may here be made to devices disclosed in the United States Patents 627781 of June 27, 1899, or 617,185, of January 3, 1899.

From the kettle 23 a flue 29 leads to the stack 19, to carry off the smoke.

The method for pitching the barrels is about as follows: The air conveyed from the 5 casing 4 into the chamber 7, is in most cases of too high a temperature for the purpose desired. By blowing air into the chamber through pipe 9, a draft is created in the chamber facilitating the inflow of the heated 10 air, and the temperature of the air in the chamber is reduced to a suitable degree to melt pitch. At the same time the volume of the air is considerably increased and a rapid 15 whirling motion is imparted to the same, so that the air from the chamber flows at high speed into the pipes 11 and 12. When barrels are placed in the seats 15, so that the nozzles 16 project into the interior of the barrels the hot air forcibly injected through 20 the nozzles will have the same effect as the open flame, heretofore utilized for removing the old coating of pitch. The danger of fire is avoided and the obnoxious odor and smoke 25 eliminated. The latter are removed through flues 18 and stack 19. The barrel is then coated with new pitch by means of the pitching device 14. In the suction stroke of the pump liquid pitch is drawn into the tank and in the pressure stroke it is discharged 30 therefrom through the nozzle 27, into the interior of a barrel on the seat 25.

I claim:

1. In an apparatus for pitching barrels, 35 the combination of a pitch kettle, a plurality of injector nozzles, a burner, an air chamber, means for conveying air heated by said burner into the chamber, means for imparting a rapid, whirling movement to the air in said chamber, and means for convey-

ing the air from said chamber to said kettle 40 and to said nozzles.

2. In an apparatus for pitching barrels, the combination of a pitch kettle, a plurality of injector nozzles, a burner, an air chamber, means for conveying the air heated 45 by said burner into said air chamber, means for imparting a rapid, whirling movement to the air in said chamber, and pipes for conveying the air from the said chamber simultaneously to said pitch kettle and to 50 said nozzles.

3. In an apparatus for pitching barrels, the combination of a pitch kettle, a plurality of injector nozzles, a burner, a circular air chamber, means for conveying air 55 heated by said burner into the air chamber, a blower, a pipe extending from said blower into said air chamber, said pipe being disposed tangentially with respect to a circle concentric with the air chamber, and pipes 60 for conveying the air from said air chamber to said pitch kettle and to said nozzles.

4. An apparatus for depitching barrels, comprising in combination, a burner, an air chamber, means for conveying the air heated 65 by said burner, into said chamber, means for imparting a whirling movement to said air, an injector nozzle, a barrel seat associated with said nozzle, means for conveying air from said chamber to the nozzle, and means 70 for removing smoke from said barrel seat.

Signed at Chicago, county of Cook, State of Illinois, this 28th day of June, 1912.

HARRY TORCHIANI.
